CHALK HOLDER

Julius J. Fleischmann, Chicago, Ill., assignor to
The Brunswick-Balke-Collender Company, Chi-
cago, Ill., a corporation of Delaware

Application September 5, 1940, Serial No. 355,477

11 Claims. (Cl. 273—54)

This invention relates to a chalk holder for use in connection with bowling alleys. It is customary to provide a block of chalk, usually in the form of a truncated cone, and mounted conveniently adjacent the alley for the use of the players in chalking their hands as a preparation for play. Ordinarily, the chalk cone is supported on the newel post, at which the return track for the bowling balls terminates.

One object of the invention is to provide means for firmly securing the chalk in a position for use.

Another object is to provide a base assembly adapted to be attached to the base portion of the cone and provided with anchoring means engageable with cooperating means on the newel post or other support.

A further object is to provide a simple, durable and ornamental mounting for a chalk cone adapted to enhance the appearance of the structure to which it is applied.

And it is also an object of the invention to provide a holding structure for a chalk cone designed to engage the cone firmly without danger of chipping or cracking it, and to be readily releasable to permit replacement of the cone.

Other objects and advantages will become apparent from the following detailed description taken in connection with the accompanying drawings in which:

Figure 1 is a perspective view showing the upper portion of a newel post with the chalk cone mounted therein by means embodying this invention.

Figure 2 is a vertical section taken substantially at the axis of the cone, as indicated at line 2—2 on Figure 1 and on a larger scale.

Figure 3 is a top plan view taken partly in section, as indicated at line 3—3 on Figure 2.

Figure 4 is an elevation, partly in section, showing a chalk cone and a modified form of holding structure therefor.

Figure 5 is a transverse section taken as indicated at line 5—5 on Figure 4.

Figure 6 is a detail section taken as indicated at line 6—6 on Figure 4.

While I have shown in the drawings, and shall herein describe in detail two forms of my invention as embodied in chalk cone holders, each designed to be mounted on a newel post, it is to be understood that I do not thereby intend to limit the invention to these specific forms or to combination with the particular mounts disclosed, but aim to cover all modifications and alternative constructions falling within the spirit and scope

of the invention as expressed in the appended claims.

Figure 1 illustrates a newel post 10 with a fragment of the return track 11 for bowling balls extending therefrom, and with an ornamental metallic cap 12 which is shown as including an ash tray 13, and from which the chalk cone 14 rises in convenient position for use by the players. Figure 2 shows the chalk cone 14 in section, with a metallic mounting flange 15 externally tapered so as to fit snugly over the cone near its base. Against the flat base surface of the cone there is secured a metallic bottom plate 16 which is formed with a central boss 17, dimensioned to fit into the usual central axial bore 18 of the cone. The cap 12 of the newel post includes a peripheral flange or skirt 19 which overhangs the upper end of the post and conforms to its contour, but is not permanently attached thereto. Thus, when desired, the entire cap may be lifted off the post for adjusting or removing the chalk cone. The cap 12 includes a circular opening into which there is fitted a pan or receptacle 20, and the latter is supported by its flange or lip 21 overlapping and secured to the marginal portion of the cap 12 around the opening.

The flange 15 includes a peripheral portion 22 which rests upon the cap 12 and covers the flange 21 of the receptacle 20. It also has an annular portion 23 which fits approximately within the receptacle 20. Depending hangers 24 extend from the annular portion 23 downwardly past the bottom plate 16 and support a three-armed spider 25 having a threaded hub 26. A threaded stud 27 is adjustably carried in the threaded hub 26 and extends upwardly into a socket 17a in the boss 17 of the bottom plate 16. The stud 27, when adjusted to bear against the end wall of the socket 17a, also exerts pressure downwardly which is transmitted by the end portions 28 of the arms of the spider 25 to the flanges 24a of hangers 24 on which these arms are lodged, so that the hangers act to draw the internally tapered flange 15 snugly onto the chalk cone 14; and, incidentally, the lower end portion 27a of the stud 27 is then held rigidly projecting from the hub 26 of the spider. With the parts thus adjusted a set screw 29 in the hub 26 is employed to maintain the adjustment, impinging against the surface of the stud 27.

It may be understood that the flange 15, bottom plate 16 and spider 25 are applied to the chalk cone preparatory to placing it in position on the cap 12. To facilitate positioning the

arms of the spider 25 the hangers 24 are formed with stop flanges 24^b. The ends 28 of the spider arms are entered in the intervals between the hangers 24, as shown in dotted lines in Figures 5 and 6, and then rotated into engagement with the stops 24^b, where they are registered for lodgment on the flanges 24^a of the hangers. Adjusting the threaded stud 27 then shifts the spider arms into contact with the flanges 24^a for drawing the assembly snugly onto the chalk cone 14.

The projecting lower end of the stud 27 is passed through a central aperture in the bottom of the receptacle 20 as the cone 14 is centered therein, and the assembly is then secured in position by means of a clamping spider 30 screwed onto the end portion 27^a of the stud. A set screw 31 in the hub of the spider 30 serves to maintain this relation. As indicated in the drawing, the end of the stud 27 and the exposed ends of set screws 29 and 30 are formed with hexagonal sockets to receive a suitable tool, in the nature of a key or wrench, for tightening these threaded members or releasing them, as desired.

When the cone 14 has been thus positioned and attached to the cap 12 the latter is fitted in position over the end of the newel post 10; and when replacement of the cone 14 becomes necessary the cap 12 is merely lifted off the newel post to afford access to the fastening means just described.

Figures 4, 5 and 6 illustrate a slightly modified construction in which the cone 14 and flange 15 are substantially similar to the corresponding parts already described. The flange 15 also includes the depending hangers 24 which engage and support the arms of a spider 25, and these parts are held firmly in position by means of a threaded central stud 27 extending through the hub 26 of the spider and impinging against the central portion of the bottom plate 16, contracting the base of the cone 14 exactly as in the form shown in Figures 1 to 3.

But in this case the hollow newel post 40 is surmounted by a permanently attached metallic finish cap or flange 41 having a central opening into which the hangers 24 extend while the flange 15 rests upon the marginal portion of the cap 41 surrounding this opening. The post 40 may be of hollow construction, and at a short distance below the cap 41 there is disposed therein a threaded metallic fitting 42 supported upon a block 43 secured centrally in the hollow post 40. The fitting 42 is in the form of a boss having a foot flange 44 through which mounting screws 45 extend into the block 43. The bore of the boss 42 is threaded to receive the projecting lower end 27^a of the stud 27 so that after the flange 15, bottom plate 16, spider 25 and stud 27 have been assembled on the lower end of the chalk cone 14, the cone may be anchored on the newel post by merely entering the end 27^a of the stud in the threaded bore of the boss 42 and turning the cone until the flange 15 fits snugly against the cap 41. Reverse rotation of the cone will release it from the supporting post when the chalk has been used up or requires replacement.

I claim as my invention:

1. A holder for a tapered block of chalk comprising a mounting flange internally tapered to fit the block near its base, a bottom plate engageable with the lower end of the block, a centrally threaded member disposed below the bot-

tom plate, means connecting said member and the flange laterally beyond the block, and a threaded stud extending from said threaded member and bearing against the bottom plate to draw the flange snugly onto the tapered block.

2. A holder for a tapered block of chalk comprising a mounting flange internally tapered to fit the block near its base, a bottom plate engageable with the lower end of the block, a centrally threaded member disposed below the bottom plate, means connecting said member and the flange laterally beyond the block, and a threaded stud extending from said threaded member and bearing against the bottom plate to draw the flange snugly onto the tapered block, together with a support and means to anchor said block thereon by engagement with said stud.

3. A holder for a tapered block of chalk comprising a mounting flange internally tapered to fit the block near its base, a bottom plate engageable with the lower end of the block, a centrally threaded member disposed below the bottom plate, means connecting said member and the flange laterally beyond the block, and a threaded stud extending from said threaded member and bearing against the bottom plate to draw the flange snugly onto the tapered block, the opposite end of the stud projecting below said threaded member, a support on which said flange rests, and threaded means anchoring said stud to the support.

4. A holder for a tapered block of chalk having an axial bore, said holder comprising a mounting flange internally tapered to fit the block near its base, a bottom plate engageable with the lower end of the block and having a central boss to fit the bore thereof, a centrally threaded member disposed below the bottom plate, means connecting said member and the flange laterally beyond the block, and a threaded stud extending from said threaded member and bearing upwardly in a socket formed in the boss of the bottom plate to draw the flange snugly onto the tapered block.

5. A holder for a tapered block of chalk comprising a mounting flange internally tapered to fit the block near its base, a bottom plate engageable with the lower end of the block, said flange having depending hangers extending below the plane of the bottom plate, a spider having a centrally threaded hub and arms radiating therefrom engaged with said hangers, and a threaded stud extending from said hub and bearing against the bottom plate to draw the flange snugly onto the tapered block.

6. A holder for a tapered block of chalk comprising a mounting flange internally tapered to fit the block near its base, a bottom plate engageable with the lower end of the block, said flange having depending hangers extending below the plane of the bottom plate, a spider having a centrally threaded hub and arms radiating therefrom engaged with said hangers, and a threaded stud extending through said hub and bearing against the bottom plate to draw the flange snugly onto the tapered block, together with a support having an upwardly open cavity to receive the lower end of the block and having a transverse wall forming the bottom of the cavity at a distance below the level of the mounting flange with threaded means securing the lower end of the stud to said transverse wall.

7. A holder for a cone of chalk comprising a ring internally tapered to fit the cone near its

base with means extending downwardly from the ring past said base of the cone, a member disposed below the cone and engaged with said means, and an element adjustable in said member to bear against the base of the cone for drawing the ring into snug engagement with its tapered surface.

8. In combination with a support having an upwardly open cavity, a holder for a cone of chalk comprising a ring tapered to fit the cone near its base and dimensioned for lodgment upon the marginal surface of the support adjacent said cavity, said ring having means extending downwardly past the base of the cone into the cavity, a threaded member disposed below the cone and engaged with said means, and a threaded element adjustable in said member to bear against the base of the cone for drawing the ring into snug engagement with its tapered surface, together with additional threaded means securing the lower end of said threaded element to the bottom of the cavity.

9. In combination with a support having an upwardly open cavity with a transverse bottom wall and an upwardly open threaded socket secured thereto, a holder for a cone of chalk comprising a ring internally tapered to fit the cone near its base with hangers extending downwardly from the ring past said base of the cone, a spider disposed below the cone and having a central threaded hub and arms radiating therefrom engaged with said hangers, and a threaded stud adjustable through said hub for exerting pressure against the base of the cone to draw the ring into snug engagement with its tapered surface, the lower end of said stud projecting for engagement

in the socket for anchoring the cone to the support with said ring lodged on the rim of the cavity.

10. In combination with a post having an upwardly open cavity and a cap for the post having a marginal flange and a recessed portion suspended within the cavity of the post, a holder for a cone of chalk comprising a ring internally tapered to fit the cone near its base and dimensioned to rest on the marginal portion of the cap surrounding said recessed portion with means extending downwardly from the ring past said base of the cone, a centrally threaded member disposed below the cone and engaged with said means, a threaded stud in said threaded member adjustable to bear against the base of the cone for drawing the ring into snug engagement with its tapered surface, the recessed portion of the cap having an aperture through which said stud extends, and a nut secured to said extending end of the stud under the cap for anchoring the cone in position in the recess.

11. A holder for a cone of chalk comprising a ring internally tapered to fit the cone near its base with means extending downwardly from the ring past said base of the cone, a member engaged with the base of the cone, a member disposed below the cone and connected by said means with the ring, and an element having threaded engagement with one of said members and adjustable therein to bear against the other in a direction to separate them and draw the ring into snug engagement with the tapered surface of the cone.

JULIUS J. FLEISCHMANN.
